(57) **CLAIM**

The ornamental design for a bullpup firearm, as shown and described.

DESCRIPTION

FIG. 1 is a right-side/front perspective view of the bullpup firearm

FIG. 2 is a right-side/rear perspective view of the bullpup firearm.

FIG. 3 is right elevation of the bullpup firearm.

FIG. 4 is a left elevation of the bullpup firearm.

FIG. 5 is rear elevation of the bullpup firearm.

FIG. 6 is a front elevation of the bullpup firearm.

FIG. 7 is top plan view of the bullpup firearm.

FIG. 8 is a bottom plan view of the bullpup firearm.

FIG. 9 is an alternate right-side/front perspective view of the bullpup firearm.

FIG. 10 is an alternate right-side/rear perspective view of the bullpup firearm.

FIG. 11 is a left-side/rear perspective view of the bullpup firearm.

FIG. 12 is a left-side/front perspective view of the bullpup firearm.

FIG. 13 is an alternate left-side/front perspective view of the bullpup firearm; and,

FIG. 14 is an alternate left-side/rear perspective view of the bullpup firearm.

The broken lines in the figures depict the firearm barrel and surface ornamentation that are illustrative of environment and not intended to form a part of the claimed design.
